(57) **CLAIM**

The ornamental design for a toothbrush for children, as shown and described.

DESCRIPTION

FIG. 1 is a perspective view of my new design for a toothbrush for children;

FIG. 2 is a front elevation view of my new design;
FIG. 3 is a left-side elevation view, the right-side elevation view being a mirror image thereof;

FIG. 4 is a rear elevation view thereof;

FIG. 5 is a top plan view thereof; and,

FIG. 6 is a bottom plan view thereof.

The broken lines are for illustrative purposes only and form no part of the claimed design.
